UNITED STATES PATENT OFFICE

CARL M. F. FRIDEN, OF OAKLAND, CALIFORNIA, ASSIGNOR TO MARCHANT CALCULATING MACHINE COMPANY, OF EMERYVILLE, CALIFORNIA, A CORPORATION OF CALIFORNIA

CALCULATING MACHINE

Application filed September 17, 1928. Serial No. 306,337.

The invention relates particularly to calculating machines of the key-board type, into which values are introduced by impulses on the keys. Impulse on a key produces 5 movement of a selector unit and the impulse is almost invariably sufficiently strong to cause the unit to overthrow and then return to its selected adjusted position.

An object of the invention is to provide 10 means whereby the selector unit is moved to selected adjusted positions by impulse on a key, and is prevented from overthrowing.

The invention possesses other advantageous features, some of which with the 15 foregoing will be set forth at length in the following description, where I shall outline in full that form of the invention which I have selected for illustration in the drawing accompanying and forming part of the present specification. In said drawing, I have shown one form of my invention, but it is to be understood that I do not limit myself to such form, since the invention, as set forth in the claims, may be embodied in a plurality 25 of forms.

The drawing is a vertical longitudinal section through a calculating machine, showing one embodiment of my invention.

The invention is shown embodied in a calculating machine of the general type disclosed in my prior United States Patent No. 1,643,710, of September 27, 1927. This type of calculating machine embodies an actuator comprising a plurality of rotatably mounted selector units, which are moved to adjusted 35 selected positions by impulse on the keys of the key-board. Ten keys, of different numerical value, from zero to nine, inclusive, are associated with each selecting unit and depression of a key sets the unit in adjusted 40 position corresponding to the value of the depressed key. Means are provided which are operative, upon initial movement of the actuator, to lock the selecting element in adjusted 45 position and, if the actuator is thrown into operation immediately after the key on the key-board has been struck, the locking means may engage the selector unit, while such unit is in an overthrown position, there- 50 by causing the introduction of an error into

the machine. Due to the impulse on the key, the selector unit may be thrown past its proper selected position, to which selected position it is then returned by a spring, but, if the actuator is thrown into immediate 55 operation, it sometimes occurs that the selector unit is locked in an overthrown position. The object of the present invention is to prevent overthrow of the selector unit without interfering with the ready positioning thereof and without increasing the key pressure required to set the key.

The drawing shows only such parts of the calculating machine as are required to disclose the present invention, reference being had to the aforementioned Letters Patent for a disclosure of a complete calculating machine. Values are introduced into the machine by selectively setting the selector units of the actuator. Each of these units 2 is rotatably mounted on the actuator shaft 3 and is suitably connected to a row of keys of different numerical values, so that the selector unit is differentially positioned by depression of a selected key. Usually, ten keys 4 are associated with each selector unit, the front key being the zero key and the rear key being the nine key. Each key includes a key stem 5, provided with means for locking it in depressed position, a usual form being a cam 6 on the key stem which cooperates with a slotted spring pressed slide 7. The depressed key is thus held in depressed position until it is released by releasing movement of the slide 7 when the key is returned to elevated position by the spring 8.

Interposed between the key stems and the selector unit 2 is a motion transmitting mechanism, which is differentially movable, depending upon the value of the depressed key. The present motion transmitting mechanism comprises a key-bar 12 pivoted at its rear end on the shaft 13 and lying below and being disconnected from the stems 5 of the keys. The key-bar 12 being separate from the key stems 5, impulse on a key imparts momentum to the key-bar 12, which tends to move it downward a greater distance than the downward movement of the key stem, and this excess of movement has caused the 100

overthrow of the selector unit. Movement is transmitted from the key-bar 12 to the selector unit 2 through the bell crank lever 14, pivoted on the shaft 15 and provided at one end with a pin 16, seated in a slot 17 in the key-bar, and provided at its other end with an arcuate rack 18, which is in mesh with a gear 19, secured to the selector unit. The selector unit is normally held in zero position 10 and the key-bar 12 is normally held in elevated position by the spring 21, secured to the bell crank lever 14.

Means is provided for locking the selector unit in adjusted position, and this means 15 is brought into operation upon the initial movement of the actuator, which is secured to the shaft 3, from full cycle position. In the present instance, this means comprises a cam 22, secured to the actuator shaft 3, and 20 having a depressed portion, which is engaged by the arm 24, when the actuator is in full cycle position. The arm 24 is secured to a shaft 25, to which there is secured a plurality of locking pawls 26, there being one 25 locking pawl for each selector unit. The selector unit is provided with an arcuate rack 27, which is disposed adjacent the end of the locking pawl 26, and, when the shaft 25 is rocked, the locking pawl is moved into 30 engagement with the rack 27, locking the selecting unit in position.

The present invention provides means for preventing the movement of the selecting unit past the position corresponding to the 35 value of the depressed key. In the drawing, I have shown this mechanism in association with the keys valued from one to seven, inclusive, since I have found that it is impossible to lock the selecting unit in an overthrown position, when either the eight or the nine key has been depressed. The pin and slot connection 16—17, operates as a 40 stop to prevent movement of the selecting unit past the nine position, so that no other 45 means are necessary to prevent an overthrow by depression of the nine key. Similarly, it is impossible to operate the machine to catch the selector unit in an overthrown position when the eight key is depressed but, if desirable, the mechanism shown can readily be 50 extended to include the eight key.

Disposed below the stems 5 of the keys of the value of one to seven, inclusive, is a slide 31, mounted on brackets 32 and normally 55 held in inoperative position by the spring 33. The slide 31 is provided on its upper surface with a plurality of differentially inclined surfaces 34, which are disposed in the path of the key stems 5. The inclination of 60 the various surfaces 34 is different, so that upon depression of a key 4, the amount of movement of the slide 31 is a function of the value of the depressed key. Depression of the one key causes the greatest movement of 65 the slide and depression of the seven key

causes the smallest movement of the slide. It is seen, therefore, that upon depression of a key 4 the slide 31 is differentially moved a distance inversely proportional to the value of the depressed key. This movement is employed to limit the downward movement of the key-bar 12 to the differential position corresponding to the value of the depressed key, thereby preventing overthrow of the selector unit. The selector unit 2 is positively connected to the key-bar 12 so that by limiting the downward movement of the key-bar to its proper differential position, the rotating movement of the selecting unit is also limited, so that such unit does not move beyond its proper differential position. The pin slot connection 16—17, prevents movement of the selector unit independently of the key-bar. 70 75 80

At its forward end, the key-bar 12 is provided with a pin or roller 35 and, at its forward end, the slide 31 is provided with a surface 36, so formed that it forms an abutment for the roller 35, when the key-bar 12 has moved downward a distance corresponding to the value of the depressed keys. Upon 90 depression of any key, the key-bar 12 moves downward and the slide 31 moves forward, bringing the roller 35 and the surface 36 into contact when both the slide and the key-bar have moved the differential distances corresponding to the value of the depressed key, thus locking the key-bar 12 against further downward movement and consequently preventing overthrow of the selector unit. 95

I claim:

1. In a calculating machine, a plurality of impulse operated keys, a pivoted key bar positioned below the keys, a movable unit connected to said key-bar and a slide moved by the keys into engagement with the key bar 10 to limit downward movement of the key-bar.

2. In a calculating machine, a plurality of impulse operated keys of different values, a pivoted key-bar arranged below the keys and separate therefrom and adapted to be 110 differentially positioned thereby, a movable unit connected to the key-bar, a slide arranged below the keys and separate therefrom and adapted to be differentially positioned thereby and means on the key-bar adapted to 115 engage the slide to prevent further movement of the key-bar upon the completion of the selected differential movement of the key-bar.

3. In a calculating machine, a plurality of 120 depressible keys of different values, a differentially movable key-bar associated therewith, and a differentially movable slide arranged to be moved by depression of a key to engage the key-bar to limit the movement of the key-bar to a magnitude corresponding to the value of the depressed key. 125

In testimony whereof, I have hereunto set my hand.

CARL M. F. FRIDEN. 130
